SYRINGE

Paul S. Madsen, Bethany, and Arthur A. Arnold, Hamden, Conn., assignors to The Seamless Rubber Company, New Haven, Conn., a corporation of Connecticut

Original application July 28, 1941, Serial No. 404,382. Divided and this application June 15, 1942, Serial No. 447,032

6 Claims. (Cl. 128—229)

This invention relates to syringes, the present application being a division of our application Serial No. 404,382, filed July 28, 1941, now Patent No. 2,317,545, dated April 27, 1943.

One of the objects of the invention is the provision of a syringe in which the syringe tube can be readily applied to and detached from the water receptacle, so that the water receptacle is adapted to serve in other capacities than as a part of a fountain syringe, the device having an improved form of connection between the syringe tube and the receptacle which greatly facilitates manipulation and use.

Another object which we have in view is to provide an improved fountain syringe of the elastic-bag type.

To these and other ends the invention consists in the novel features and combinations of parts to be hereinafter described and claimed.

In the accompanying drawing:

Fig. 1 is a face view of a device embodying our improvements, showing the same in position for use as a fountain syringe;

Fig. 2 is an enlarged section on line 2—2 of Fig. 1;

Fig. 3 is a sectional view of a portion of the receptacle with the syringe tube detached and the valve closed; and

Fig. 4 is an enlarged section on line 4—4 of Fig. 1.

In the drawing, we have shown at 10 a receptacle adapted to be supported from its upper end on a suitable supporting wall or the like. At 11 is shown a syringe tube adapted to be plugged into or removed from the receptacle, the connection between the tube and the receptacle being generally indicated at 12.

The receptacle 10 in this particular instance is a flat rectangular bag of rubber, adapted to serve under certain conditions as a water bag or ice bag, and provided with a special end closure, as described in our Patent No. 2,273,128, dated February 17, 1942. This special end closure is generally indicated at 13 in Fig. 3, and it will be seen that when used for fountain syringe purposes this end closure is at the lower end of the bag, with the connection 12, previously mentioned, located slightly above the end closure. The connection 12 enables the rubber syringe tube 11 to communicate with a water chamber in the bag, the bottom wall of the water chamber being constituted in part by a partition 14, from which extends a rollable neck 15, as described in the application above mentioned.

The connection 12 comprises as a part thereof

a valve housing 16, formed integrally with the walls of the rubber bag, a part of this housing preferably merging into the partition 14, as shown. Within the valve housing 16 is a valve plug 17. This valve plug 17, which is made of rubber, is provided with a laterally extending flange 18 adapted to seat in an annular recess 19 formed in the bore of the valve housing. In this manner the valve plug is removably held in place. The valve plug is provided with an opening or socket 20 extending inwardly from the outer end thereof part way through the valve body. From the inner end of this opening 20 to the inner end of the valve plug, the plug is split longitudinally at 21 so as to divide it into two separable parts. In the normal position, however, these parts are held together under strong compression by an inner ring-like integral rubber part of the valve housing, indicated at 22.

The syringe tube 11 is provided at its free end with a nipple member 23, having a body of reduced diameter compared to the syringe tube, which body is adapted to be inserted into the valve plug in the manner shown in Fig. 2. The nipple is inserted through the opening in the plug and between those portions of the plug at opposite sides of the slit. This causes the inner end portions of the valve plug or member to be spread apart against the yielding action of the surrounding elastic valve housing so that the nipple will be in free communication with the interior of the receptacle. It will also be apparent from Fig. 3 that when the nipple is withdrawn the elastic portions of the valve member on opposite sides of the slit will be returned to the tightly abutting relation so as to seal the valve opening effectively against leakage.

As the valve is a self-closing valve, no screw stopper or similar closing device is required, which may become loose in the use of the article. It is only necessary to insert the nipple into the socketed valve body to establish connection of the tube 11 with the liquid receptacle so as to adapt the device for use as a fountain syringe, and it is only necessary to withdraw the nipple used with the self-closing valve, in order to convert the device into a water bag or ice bag.

When the bag is suspended on a supporting wall, it may be engaged with a nail, hook or the like, entering a small opening 24 near the upper edge of the bag. This opening 24 is provided in a thick wall portion 25, having a slot 26 open to the edge of the bag. In case a hook is used, the free end thereof may be accommodated in

the slot 26. This obviates the necessity of providing a projecting tab on the bag.

It will be noted that the connection between the syringe tube and the bag body is located at one of the side faces of the bag, and that the axis of the valve member is arranged on a slight upward and inward inclination, there being an acute angle between this axis and the lower part of the bag face at that side in which the tube is entered. This enables the tube to be inserted in an upward and inward direction, which is a matter of convenience in assembling the parts, and by this arrangement, also, a larger, more effective valve and coupling structure may be employed than would otherwise be the case. The valve and coupling structure projects only slightly from the bag face, as shown in the drawing, and this does not detract materially from the generally streamlined appearance which the bag may have.

While we have shown a preferred embodiment of our invention, it will be noted that it is capable of being embodied in many different forms, and that various modifications and changes can be made without departure from the principles of the invention or the scope of the claims.

What we claim is:

1. A fountain syringe comprising an elastic bag provided with a filling opening, a flexible syringe tube intended to be connected to the bag so that a controlled flow of liquid may pass through the tube from the bag, and a common means provided on the bag for securing the one end of the syringe tube to the bag and establishing communication between the interior of the tube and the interior of the bag, said common means providing for the removal of the syringe tube from the bag and the self-closing of the bag against leakage upon such removal, and said common means including an elastic rubber valve member held under compression in an integral elastic portion of the bag wall.

2. A fountain syringe comprising an elastic bag provided with a filling opening, a flexible syringe tube intended to be connected to the bag so that a controlled flow of liquid may pass through the tube from the bag, and a common means provided on the bag for securing the upper end of the syringe tube to the bag and establishing com-

munication between the interior of the tube and the interior of the bag, said common means providing for the removal of the syringe tube from the bag and the self-closing of the bag against leakage upon such removal, said common means including an elastic rubber valve member held under compression in an integral elastic portion of the bag wall, said valve member being constituted by a plug having an entrance portion for the tube formed with a socket, and the plug being split rearwardly of the socket and being adapted to be opened up for establishing communication of the tube with the bag interior and for effective gripping and holding of the tube end.

3. A fountain syringe comprising a flexible syringe tube, a syringe bag of elastic material carrying in one wall a valve, said valve having a rubber body with portions adapted to grip the tube from opposite sides in order to secure the tube to the bag with the bag interior in communication with the tube, said rubber valve body being held under compression in an expandable valve housing portion formed directly in the bag wall.

4. A fountain syringe having a liquid receptacle and a syringe tube, said receptacle having associated with its wall a valve, said valve comprising resilient movable means normally closing the receptacle but movable to open position by the impingement of the syringe tube.

5. A fountain syringe having a liquid receptacle and a syringe tube, said receptacle having mounted in its wall structure a valve of elastic material, said valve having a resilient movable portion normally closing the receptacle but movable to open position by the impingement of the syringe tube and provided with gripping means adapted to hold the tube to the receptacle.

6. A fountain syringe having a liquid receptacle and a syringe tube, said receptacle having mounted in association with its wall a valve, said valve having socket means to receive a nipple carried by the syringe tube and having receptacle-closing means movable to open position by the insertion of the nipple into the valve.
